CLEANER ATTACHMENT FOR SILK THROWING MACHINES

Frederick Herman Schrey, Wilkes-Barre, Pa.

Application November 4, 1936, Serial No. 109,191

1 Claim. (Cl. 28—70)

This invention relates to silk-throwing machines and has particular reference to a cleaner attachment adapted to be secured to the frame of such a machine whereby threads passing through the attachment may move freely except when waste or the like is twisted fast to the thread.

An object of the invention is the provision of a device to remove from the silk threads the bunches of waste and other foreign particles which may be attached thereto.

Another object of the invention is the provision of a cleaner comb which may be used separately or which may be used in pairs.

Another object of the invention is the provision of a comb of this type having teeth which are oval in cross section and which teeth are of uniform size in cross section throughout their lengths.

Another object of the invention is the provision of a device of this kind which may be very easily kept clean.

Another object of the invention is the provision of a device of this kind which will not break adjacent threads even though one thread may become entangled or broken.

A further object of the invention is to provide a device of this character which is adapted to cleaning all sides of a thread passing therethrough.

Other and further objects of the invention will become apparent from a reading of the following specification, taken in conjunction with the appended claim.

For a better understanding of the invention, reference may be made to the accompanying drawing forming a part of this disclosure, wherein:

Figure 1 is a plan view of the attachment.

Figure 2 is a sectional view taken along line 2—2 of Figure 1.

Figure 3 is a reduced fragmentary view of the attachment in place upon a silk-throwing machine.

Figure 4 is a plan view of a modified form of the invention, and

Figure 5 is a sectional view taken along line 5—5 of Figure 4.

Referring more particularly to the drawing there is shown therein my invention generally indicated at 10 in position upon a frame 11 of a silk-throwing machine. It will be seen that there is provided a bracket 12 which is attached to the frame by means of bolts 13 or the like. The outer end of the bracket is formed in a pair of integral arms 14 and 15 which are formed with recesses 16 and 17 respectively.

Within recesses 16 and 17 are respectively mounted combs 18 and 19 of that general type disclosed in the United States Patent Number 1,275,361 to Andrew Baker.

It will be seen that the combs are so mounted within the recesses 16 and 17 as to be capable of being placed in right angular relation to each other.

In operation, the thread 20 is first placed within one of the combs, for example, comb 18 and then in the other comb, whereupon the comb 18 is swung around into the position shown in Figure 1. It will be understood that in the ordinary operation of this device from two to six threads are passing through the device simultaneously, for example, as shown at 21 in Figure 1.

The combs are adjustably fastened to the bracket 12 by means of bolts and nuts 22.

It will be understood that threads passing through the instant device will encounter no opposition to their passage but that any adhering particles will be automatically removed from the threads by means of the combs. It will be further understood that the comb 19, for example, will remove particles from two opposite sides of a thread and that the cooperative comb 18 will remove particles from the remaining sides of the thread.

In Figures 4 and 5 there is disclosed a modified form of the invention in which a comb 23 is provided with teeth 24 having an oval cross section as clearly disclosed in Figure 5. This type of comb is even more efficient than that above described in that it presents no jagged edge whatever to the threads moving therethrough. Of course, in both types of combs, the same may be used separately or in conjunction with one another.

While but two forms of the invention have been disclosed, it will be understood that various minor modifications may be made within the scope of this invention without departing from the spirit of the same or of the appended claim.

What is claimed is:

A cleaning device for silk-throwing machines and the like, a bracket for attachment to the machine having a pair of horizontally and inwardly extending arms each having a centrally located recess and a comb adjustably mounted within the recess in each arm, one comb extending above the other and forming an angle therewith, whereby several threads may be passed through the combs simultaneously.
